UNITED STATES PATENT OFFICE.

CHARLES SINBAD, OF SAN FRANCISCO, CALIFORNIA, ASSIGNOR OF ONE-SIXTH TO
PETER J. M. BERTELSEN AND ONE-SIXTH TO ANDREW BERTELSEN, BOTH OF SAN
FRANCISCO, CALIFORNIA.

SECOND-HAND-SETTING MECHANISM FOR WATCHES.

1,244,251.

Specification of Letters Patent. Patented Oct. 23, 1917.

Application filed April 26, 1916. Serial No. 93,657.

To all whom it may concern:

Be it known that I, CHARLES SINBAD, a citizen of the United States, residing at San Francisco, in the county of San Francisco and State of California, have invented certain new and useful Improvements in Second-Hand-Setting Mechanisms for Watches, of which the following is a specification.

10 My invention relates to new and useful improvements in watches and more particularly to the setting mechanisms thereof, the primary object of my invention being the provision of a mechanism for watches 15 by means of which it is possible to set the second hand of the watch by the lever and stem employed at the present time in setting the minute and hour hands, this being accomplished without any possibility 20 of injury to the watch.

When a watch leaves a watchmaker, the minute hand and second hand should correspond, the second hand being at the 60 mark of its dial when the minute hand is 25 upon a full minute mark. Obviously, however, the hands will correspond in this manner only until the first time that the watch is reset and no satisfactory way, at present, is known for overcoming this difficulty, although two methods are commonly employed.

One way of bringing the second hand into correspondence with the minute hand of the watch is to move the second hand 35 with a pair of tweezers, a screw driver or other suitable instrument while the watch is running. The probability of breaking the roller jewels or injuring the pallet jewels or the balance pivots and like parts 40 is great if this method is followed. The other way, which is the way generally employed, is to stop the balance wheel until the second hand corresponds with the second hand upon the regulator by which the 45 watch is being set and in then setting the minute hand to correspond to the regulator. The balance wheel is commonly stopped by a feather and inasmuch as the jewels are covered with oil, oil frequently gets upon 50 the feather and from the feather to the hair-spring with the result that the watch will not keep proper time until such oil has been removed, which can be done only by removing the bridge with its balance wheel

and hair-spring from the rest of the watch. 55 To overcome this, some people employ a pin, needle or other instrument to stop the balance wheel, but this method is open to objection because of the extreme likelihood of injuring the pivots of the balance 60 wheel.

Of course, it is obvious that the better the watch and the more delicate its works, the more likely it is to be injured by improper treatment and one of the primary 65 objects of my invention consists in providing an arrangement for stopping the second hand of a watch which cannot possibly injure any portion of the watch no matter how delicate its construction may be. 70

In this connection, a further object of my invention is to provide a swinging support for the second hand pivot which may be mounted between the plates of the 75 watch in such a manner that the pinion of the second hand pivot may be swung into and out of mesh with the toothed wheel by which it is driven. Obviously, this cannot place any strain upon the jewels, pivots or other delicate portions of the watch mechanism and no injury can result. 80

A still further object of my invention is to mount the swinging support for the second hand pivot in such a manner that such pivot is firmly held in order that a second 85 hand may be adjusted upon its pivot or spindle without injuring the other parts of the watch or even removed from its pivot or spindle no matter how tightly it may be wedged or held thereon. 80

A still further object of my invention consists in the provision of a switch lever for swinging the second hand pivot carrying member into and out of normal position and in so arranging the switch lever and the ordinary setting lever of the watch that actuation of the setting lever, in the usual manner to permit setting of the watch, will actuate the switch lever to swing the pinion of the second hand pivot out of engagement with its drive wheel. 95 100

Although the switch lever acts to positively swing the second hand pivot to inactive position, I preferably depend upon the action of the spring to return the pivot 105 to active or normal position, and a still further object of my invention consists in providing an adjustable device for limit-

ing the return movement of the second hand pivot and therefore for regulating the depth to which the teeth of the second hand pinion and its drive wheel shall mesh.

- 5 Further objects of my invention are the provision of a friction spring for preventing turning movement of the second hand pivot when in inactive position, and the provision of a suitable seat upon the switch 10 lever to engage a pin carried by the pivot carrying body or member and lock it against return movement under the action of its spring until the switch lever is returned to normal position.
- 15 With these and other objects in view, my invention will be more fully described, illustrated in the accompanying drawings, then specifically pointed out in the claims which are attached to and form a part of 20 this application.

In the drawings:

Figure 1 is a fragmentary plan view of my invention applied to an eighteen size, lever set watch movement of a standard 25 open face type, a portion of the top or back plate being broken away to show the device and the correlated parts of the watch works proper.

Fig. 2 is a plan view of the lower or face 30 plate of the watch with the works removed, showing certain modifications in structure to adapt it for receipt of my improvement;

Fig. 3 is a fragmentary vertical sectional view taken through the back and front 35 plates of the watch, showing my device in elevation;

Fig. 4 is an elevation of the main portion 40 of my invention, showing the parts in un-assembled position;

Fig. 5 is a front elevation of the mechanism shown in Fig. 4, in connection with the toothed wheel which drives the second hand pivot;

Fig. 6 is an outside plan view of the 45 lower or face plate of the watch, showing my invention applied, the setting mechanism being in inactive or normal position;

Fig. 7 is a view corresponding to Fig. 6, showing the hand setting mechanism in 50 active position;

Fig. 8 is an outer plan view of the top or back plate of the watch;

Fig. 9 is an inner plan view of the same plate with the works removed;

Fig. 10 illustrates a banking screw employed in adjusting my device;

Fig. 11 is a fragmentary plan view of the watch dial with my invention applied.

Corresponding and like parts are referred 60 to in the following description and indicated in all the views of the drawings by the same reference characters.

In order to insure a clear and accurate 65 understanding of my invention, I have illustrated it in connection with the works

of an eighteen size, lever set movement, open face watch of standard type having the front or face plate 10 and back or top plate 11. It will, of course, be understood, however, that my invention may be applied to 70 any type of watch which is suitable to receive it, though a special type of watch may be made to embody my invention. In the watch illustrated in the drawings, 12 indicates the mainspring barrel and 13 indicates 75 the works in general including suitable trains of gearing between the toothed wheel of the main spring barrel, the hour and minute hand pivots, and the pivot 14 of the pinion 15 which meshes with the third 80 wheel 16 carried by the third wheel pivot 17.

Under ordinary circumstances, the third wheel 16 meshes with the pinion of the second hand pivot of the watch at all times. My invention primarily resides in providing 85 a supplemental third wheel mounted upon the pivot of the main third wheel and in so mounting the pivot of the second hand that it, together with its pinion, may be

swung to bring its pinion either into or out 90 of mesh with the teeth of the supplemental third wheel. To accomplish this, I provide a second hand pivot supporting member, indicated as a whole by the numeral 18, best illustrated in Figs. 3 to 5 inclusive of 95 the drawings and suitably prepare the back and front plates of the watch for the reception of this member and its correlated elements. The member 18 includes two body

members 19 and 20, the former of which 100 is substantially L-shaped, having an arm 21 terminating at its ends in pivots 22 and 23, the latter pivot being formed with a shoulder 24 at its point of juncture with the arm 21. These pivots are in alinement

with each other and seat in suitable bearing forming bores or holes 25 formed in the back and front plates of the watch. The inner face of the front plate about its pivot receiving bore is countersunk, as 105 shown at 26, to form a bearing for the adjacent end of the arm 21, while the shoulder 24 engages the inner face of the back plate to provide a similar bearing. Obviously, by this arrangement, the body portion 19 of 110 the member 18 is firmly supported against any movement other than a swinging movement about its pivots 22 and 23, as an axis. The other arm of the body portion 19, at its free end, is provided with an offset bulk

head 27 which is cylindrical in shape and which seats in a circular depression 28 formed by cutting away or countersinking the inner face of the back plate 11. It

should be noted at this point that this depression 28 is of such extent as to permit a limited swinging movement of that arm 115 of the body portion 19 carrying the bulk-head 27. The other body portion 20 of the

second hand pivot supporting member 18 120

is provided with an offset bulk-head 27 which is cylindrical in shape and which seats in a circular depression 28 formed by cutting away or countersinking the inner face of the back plate 11. It

should be noted at this point that this depression 28 is of such extent as to permit a limited swinging movement of that arm 125 of the body portion 19 carrying the bulk-head 27. The other body portion 20 of the

second hand pivot supporting member 18 130

is substantially rectangular in shape, being proportioned to engage against and coincide with the lower face of the horizontal arm of the body portion 19 to which it is secured by a screw 29. This body portion 20 is formed with an offset bulk head 30, corresponding to the bulk head 27, and in direct alinement therewith, this bulk head seating in the recess 31 formed in the inner 10 face of the front plate 10 of the watch and corresponding to the recess 28 in the back. At this point it should be noted that there is the same "end shake" between the pivoted end of the member 18 and the face plates 15 as between the bulk heads and face plates so that if strain is exerted to draw a second hand from its pivot that end of the arm 21 engaging the front plate and the bulk head 30 will engage the front plate at the same 20 time and so that if strain is exerted by pressing the second hand upon its pivot, the shoulder 24 and bulk head 27 will engage the back plate at the same time, with the result that the strain is uniformly taken 25 up by these bearing surfaces and all injury to the parts prevented.

A power pin 32 extends from the body portion 19, adjacent its arm 21, through the body portion 20 and through an arcuate slot 33 formed in the front plate of the watch. In like manner, a switch pin 34 extends from the body portion 19 adjacent its bulk head 27, through the body portion 20, and through an arcuate slot 35 in the front plate 30 of the watch. These pins prevent any turning movement of the body members with respect to each other, although this is merely an incidental function which they possess.

The opposed or inner faces of the bulk heads 27 and 30 are formed with cylindrical seats or recesses 36 to receive the second hand pivot 37 and the ends of this pivot are reduced and passed through bores or 45 openings 38 formed completely through the bulk heads; that end of the pivot passing through the bulk head 30 being extended to form a second hand receiving spindle 39 which not only projects through the bulk 50 head and through an arcuate slot 40 formed in the front plate, but also through a corresponding slot 41 formed in the dial 42 of the watch, as best shown in Fig. 11. Attention should be taken of the fact that the 55 ends of the second hand pivot 37, as well as the ends of the pins 32 and 34, do not, at any time, touch either the back or front plates of the watch.

The slot in the back plate 11, which receives one end of the pivot 37, provides means for oiling and as the pivot does not go completely through the slot, oil supplied therein will not run out upon the plate.

Referring to Fig. 5, it should be noted 60 that the third wheel 16 of the watch, to

which power is transmitted by the third wheel pivot 17 and which usually meshes with the pinion of the second hand carrying pivot, projects between the bulk heads 27 and 30 and is in no way interfered with by my above described device. In connection with the device thus far described, I provide the second hand pivot with a pinion 43 and the third wheel pinion with a supplemental third wheel 44. These correspond to the ordinary third wheel and second hand pinion, with the exception that both the pinion and wheel have double the usual number of teeth in order that they may split seconds as the pinion is swung 80 into and out of engagement with the supplemental third wheel. As a means for preventing continued turning or over-turning of the second hand pivot, when its pinion is out of engagement with the supplemental third wheel, I provide a very light friction spring 45 of the leaf spring type which is secured at one end to the intermediate portion of one side of the body portion 19 of the member 18 and which, at its 90 other end, engages tangentially against the pivot 37. This friction spring also keeps the second hand from trembling.

As will be seen by referring to Figs. 6 and 7 of the drawings, the outer face of the 95 front plate 10 of the watch is countersunk to provide a circular recess 46 and further countersunk to provide an arcuate recess 47 extending from the recess 46 to the countersunk recess 48 in which the ordinary hand setting lever and yoke operate. Both the power and switch pins 32 and 34 extend into the recesses 46 and 47, respectively, and a spring 49 secured in any recess 46 engages the end of the power pin to normally hold the second hand pivot carrying member 18 in such position that the second hand pinion 43 is held in mesh with the supplemental third wheel 44. In order to properly adjust the depth to which the teeth of this pinion and 100 wheel shall intermesh, I provide a banking screw 50 which, as best shown in Fig. 10, includes a threaded body portion having a doubly slotted end to receive a screw driver and an eccentrically formed banking pin 115 51 extending from its opposite end. This screw is threaded inwardly through the face plate 10 through an opening 52 so disposed that the banking pin 51 will engage the side of the pivot holding member 18 and adjustably limit its swinging movement into active position. The plates 10 and 11 are preferably formed with small openings or peck-holes 50' through which the intermeshing teeth of the pinion 43 and supplemental 120 third wheel 44 are disclosed in order to facilitate adjustment by means of the banking screw.

Having thus described the improved means for swingingly supporting the second 125

hand carrying pivot of the watch in such a manner that the second hand pinion may be moved into and out of engagement with the supplemental third wheel, I will now 5 explain the means by which the ordinary hand setting mechanism of the watch may be utilized to effect the swinging of the second hand pivot to unmesh its pinion from the supplemental third wheel. Referring 10 more particularly to Figs. 6 and 7 of the drawings, 53 indicates the usual hand setting yoke and 54 the yoke spring. This yoke is provided with the usual finger 55 engageable by one arm of a bell crank setting lever 56, the opposite arm of which is formed with an arcuate extension 57 which projects through the side of the watch casting and terminates in an offset finger piece 58 by means of which the arm 57 may be 20 drawn to extended position to swing the lever 56 to the position shown in Fig. 7 against the action of the yoke spring 54. This movement of the yoke, of course, brings the usual hand setting pinion 59 into mesh 25 with the wheel 60 so that the hour and minute hands may be set by the stem 61 of the watch, in the usual manner. With my improved watch construction, I provide the recess 48 with an arcuate extension 62 forming 30 a continuation of that portion of the recess in which the arcuate terminal of the setting lever 56 swings and provide that arm of the lever 56 having the extension 57 with an oppositely directed arcuate extension 63 forming a continuation of the extension 57 and having its outer edge cut away to provide an elongated notch 64. Pivoted intermediate its length by a screw 65 and seating in the arcuate recess 47, previously 40 mentioned, is a switch lever 66 forming part of my present invention. This switch lever, at one end, is formed with a finger 67 which seats in the notch 64 and at its opposite end is formed with a head having a cam face 68 adapted to engage the switch pin 34 upon outward movement of the arm 57 of the setting lever to swing the second hand pivot supporting member 18 and hold it with the second hand 50 pinion 43 out of mesh with the supplemental third wheel 44. Obviously, as soon as the arm 57 of the setting lever 56 is pressed inwardly to normal position, the yoke spring will return the yoke to normal position and the power spring 49 will return the second hand pivot supporting member 18 to normal position to bring the pinion 43 into mesh with the supplemental third wheel 44.

The operation of setting a watch equipped 60 with my improved second hand setting device is as follows:

The operator places his finger upon the setting lever 56 and watches the second hand move until it reaches the mark 60 when he 65 pulls out the setting lever, moving the second

hand pinion out of engagement with the supplemental third wheel and, consequently, stopping its movement. The operator then turns the stem of the watch to bring the hour and minute hands to the right position, according to the regulator or chronometer by which the watch is being set and holds the minute hand of the watch in accordance with the minute hand of the timing regulator or the chronometer until the second hand 70 on the regulator or chronometer reaches the 60 division of the second hand dial when he pushes in the setting lever to bring the second hand pinion into mesh with the supplemental third wheel. When this operation had been performed, the watch is properly set and all its hands correspond as they should. Upon pulling out of the setting lever, the second hand, which at that time was on the 60 mark of the second hand dial, is swung backward one or more divisions of the dial, due to the swinging action. This second hand will, however, move forward a corresponding amount, also due to the swinging action, when the setting lever is 80 pushed in and the second hand carrying member returned to normal position. This rearward swinging movement of the second hand need not, therefore, be considered in setting the watch. Obviously, with the second hand pinion in inactive position, or out of mesh with the third wheel, the second hand may be turned upon the pinion or removed and replaced by another without any injury to the watch no matter how delicate 90 its works may be.

Although I have referred to the plates 10 and 11 as front and back plates, it will be understood that I do not wish to be limited to the plates shown, as I intend, by the term 105 "plate" to cover not only the relatively solid plate but also skeletonized plates, bridges and other supporting members employed in watch construction. The word "plate," both in the specification and claims, should, 110 therefore, be construed as including plates, bridges and like structures.

Having thus described the invention, what is claimed as new is:

1. In a watch, the combination with back 115 and front plates, a train of gearing between the plates, and a setting lever extensible to bring certain of the gears into position to permit setting of the hour and minute hands, of a second hand pivot mounted for movement toward and away from one of the elements of the gearing and for turning movement but held against other movement, a second hand pinion mounted on the pivot and adapted in one position of the pivot, to mesh with an 120 element of the gearing, means normally holding the pivot in such position, an arcuate notched extension formed upon the setting lever, and a switch lever pivotally mounted with one end seating in the notch of the set- 125

ting lever, whereby swinging of the setting lever swings the switch lever and with its other end operatively disposed to swing the second hand pivot to move its pinion out of mesh with the element of the gearing.

5 2. In a watch, the combination with a train of gearing and a setting lever extensible to bring certain of the gears in position to permit setting of the hour and minute hands, of a second hand pivot mounted for movement toward and away from one of the elements of the gearing and for turning movement, a pinion mounted on the pivot to be moved in and out of mesh with such 10 element of the gearing, and means co-acting between the setting lever and pivot for swinging the pivot.

15 3. In a watch, the combination with a train of gearing and a setting lever extensible to bring certain of the gears in position to permit setting of the hour and minute hands, of a second hand pivot mounted for movement toward and away from one of the elements of the gearing and for turning 20 movement, a pinion mounted on the pivot to be moved in and out of mesh with such element of the gearing, and means co-acting between the setting lever and pivot for swinging the pivot, said means including a lever 25 operatively engaging the pivot and setting lever.

30 4. In a watch, front and back plates, a

train of gearing between the plates, the plates being formed with a pair of aligned pivot receiving openings and in spaced relation with a second pair of aligned pivot receiving openings, one of the plates about one of the first openings being formed in its inner face with a recess and both plates about the second pivot receiving openings 35 being formed in their inner faces with recesses, a member mounted between the plates and having pivots engaging in the first pivot receiving openings, the pivots being at one end of the member and the member at such 40 end being formed with a shoulder to engage against one plate and with a bulk head to seat in the recess of the other, bulk heads formed upon the opposite end of the member and seating in the recesses surrounding the 45 pivot openings, these pivot openings being in the form of slots concentric with the first pivot openings, a second hand pivot journaled in such end of the member and projecting in the slots, a pinion carried by the pivot 50 and adapted to mesh with one of the gears, pins projecting from the member through slots formed in one of the plates, means co-operating with one of the pins for normally holding the member in one position, and 55 means co-operating with the other pin for moving the member to another position.

In testimony whereof I affix my signature.

CHARLES SINBAD. [L. s.]
